UNITED STATES PATENT OFFICE

WADE F. WEBB, OF OAKLAND, CALIFORNIA

CONCRETE GUN

Application filed September 21, 1926. Serial No. 136,848.

My invention relates to a device for forcibly impelling by means of compressed air or some other suitable fluid substance, concrete or the like in a plastic state, through a conduit and into suitable forms, and especially relates to the pneumatic discharge of concrete at a comparatively low velocity and with a minimum air consumption due to the low air pressure used.

10. In other types of devices used for this purpose, two or more jets of air are used for forcing concrete or the like from the container and conveying same through the conduit. It is recognized that with the use of 15 two or more air jets an excess of air is consumed due to the fact that the amount of concrete in front of the effective or conveying jet is variable; at times little or no concrete is in front of the jet and air is wasted; and at other times too much concrete is in 20 front of the jet and a plug occurs in the reducer of the container. It is further recognized that due to the nature of the material, concrete cannot be forced from a large 25 container to a comparatively small conduit by the same method as would be used for water, that is, by pressure applied in the rear of the mass; if this method is resorted to the concrete will plug in the reducer, and the 30 more pressure applied the harder the plug will become and the container must be opened and the plug broken up by hand. To avoid 35 clogging and to continuously and successfully feed concrete from the container to the conduit the amount of concrete in front of the delivery jet should never exceed the capacity of the conduit.

It is the object of my invention to supply 40 a device in which clogging may be entirely avoided; and a further object, to supply a device with means for preventing excessive use of compressed air; and further, to supply a means for breaking a plug, without opening the container, should same occur from 45 improper manipulation or otherwise.

Other and ancillary objects and purposes will be outlined in the specification accompanying and forming part of this application, and further purposes will be suggested by the particular uses my improved device 50 encounters.

In the drawings:

Figure 1 is a longitudinal median section of the gun of my invention, and Fig. 2 is an enlarged plan of the air-nozzle in detail. 55

A substantially cylindrical container 2 tapers to an ejection throat 4 at its lower portion, is provided with an opening at 6 for the concrete supply 7, a fluid-tight closure 8 for said opening, and a source 10 of compressed air leading to an air nozzle 11 for 60 ejecting the concrete.

The ejection throat 4 may lead directly to a concrete delivery spout, or may be connected to a pipe line for conveying the concrete. It is preferably tapered as shown, to 65 provide a reducer facilitating entrance of the concrete into the ejection line.

The opening at 6 is provided with a neck 12 into which the concrete mixture may be 70 dumped to fill the gun. The air pressure in the gun, and the sticky and abrasive character of the concrete require unusual means for closing this opening 6, and for this purpose I provide a wedge-shaped slit or guide-way in the neck 12, transversely of the opening 6; and a complementary wedge-shaped cover 8 for the slit. The amount of taper of the wedge is clearly shown by the sectional view of the cover in Fig. 1, and the cover 75 extends across the opening 6 to completely close it when in the left-hand position shown in the figure. The taper of the cover 8 insures a tight seat and causes the abrasive in the concrete to merely grind the cover to a 80 smooth seat rather than to damage it.

Means are provided for opening and closing the cover. A compressed air cylinder 16 has its piston 18 connected by a rod 20 directly to the cover 8; and pipes 22 and 24 85 90

lead from each end of the cylinder to manually controllable two-way valves 26 and 28. In one position, the valves communicate with the air line 10, and in the other position they lead to the atmosphere. For simplicity of description, the fact that the two valves 26 and 28 may be replaced by a single three-way valve, is ignored.

Concrete is a thick plastic mass, and in order to facilitate its flow it is necessary to feed the concrete to the conduit in an amount not in excess of the capacity of the conduit. This prevents clogging and waste of air. The nozzle 11 therefore is positioned in the bottom of the container. There is, obviously, a proper proportion of air to concrete for most efficient ejection, and this ratio depends upon such factors as the air pressure, upon the length and constriction of the ejection line, and the density and quantity of concrete in the gun. In other words the proportion for maximum efficiency is variable. The proportion may be controlled by the position of the nozzle 11 with respect to the ejection throat 4. The ratio of air to concrete tends to increase as the nozzle is placed nearer the ejection throat.

Means are provided for moving the air nozzle toward and from the ejection throat. The nozzle 11 is formed at the end of a pipe 34, the other end of which projects through an opening at 36 in the container. A packing gland 38 prevents leakage of concrete through the opening, and tends to prevent passage of air therethrough. A cylinder 40 has its axis parallel to the pipe 34 and is bolted or otherwise attached at its open end, to the container 2 in enveloping eccentric relation to the opening at 36. A piston 42 in the cylinder, is fixedly connected by an offset rod 44 to the pipe 34. This offset relation restrains the assembly from rotation. The rod 44 is merely a solid connecting bar and has no air passage formed in it. Air supply to the cylinder and nozzle will next be explained.

A manually controlled two-way valve 45 connects the outer end of the cylinder 40 selectively to the air line 10 or to atmospheric exhaust. The inner end of the cylinder 40 may be connected to the air line 10 by a manually controllable valve 46 having no atmospheric exhaust. Thus the inner (right-hand in Fig. 1) end of the cylinder cannot be directly exhausted and so its pressure cannot drop below the pressure in the container 2. An adjustable regulating valve 48 of the safety valve type, is held closed by a spring 50 and permits escape of air when the pressure difference exceeds a few pounds per square inch, from the inner end of the cylinder 40 to the nozzle pipe 34. Thus the valve 46 controls the injection of air into the container 2, while the valve 48 regulates the pressure of the air therein. The nozzle 11

is moved away from the throat 4 by pressure of air against the piston 42, this air being admitted through valve 46 while valve 45 is opened to the atmosphere, the latter relation of the valves being indicated in Figure 70. The movement of the piston 42 toward the throat 4 is produced by air admitted by valve 45 to the cylinder 40.

A rod 52 extends from one end of the piston 42 out through a packing gland 54 in the outer cylinder head 56, and has index marks cooperating with a pointer 58, to indicate the position of the nozzle within the gun. The nozzle 11 when withdrawn from the throat of the container 2 at the manually controlled and determined rate of speed, will supply a steady flow of concrete, not in excess of the capacity of the conduit, to the conduit, thus, the maximum amount of concrete may be supplied to the conduit with a minimum consumption of air and without clogging.

The action of the air on the concrete is enhanced by the shape of the nozzle orifice. As shown in the figures, the end of the pipe 34, is tapered to a slot 60 and additional apertures 62, 64 and 66, in the top and sides throw a radiating blast of air into the concrete mass. At no point shall the nozzle surfaces lie outside of the confining lines of the pipe 34, so as not to incur friction in reciprocating the nozzle 11. The cross-sectional area of slot 60 and apertures 62, 64 and 66 is preferably about equal to that of the pipe 34.

The slot 60 lies close to the bottom of the container and the air coming from this slot will dislodge all concrete from the bottom of the container and force said concrete into and through the conduit. The radiating blasts from apertures 62, 64 and 66 will dislodge all concrete above the nozzle 11 and cause said concrete to drop to the bottom of the container where it will be subject to the blast issuing from the slot 60. The air coming from apertures 62, 64 and 66 will also assist in expelling the concrete from the conduit. Should a jam occur in the throat of the container, the air supply will be shut off at valve 46 and the air pressure in the container reduced to atmosphere by means of the manually operable relief valve 68. When this has been done the nozzle 11 will be forced into the throat of the container by air pressure applied on the piston 42 through the valve 45, and air will then be supplied to the nozzle 11 with the resultant breaking of the jam. As the nozzle is retracted the remainder of the concrete will be discharged.

In operation, the gun is filled with concrete while valves 45 and 46 remain closed. The cover 8 is then closed, and the valve 46 is opened to supply air pressure at the nozzle 11. The position of this nozzle is next adjusted by manipulation of the valve 45;

being moved away from the throat by opening the valve 45 to atmospheric exhaust, and being moved toward the throat by opening the valve 45 in the opposite direction to connect with the pressure line 10. The rate of concrete ejection is regulated by means of the valve 46, and the nozzle 11 is maintained in the most effective position by control of the valve 45.

10 Where desired, the cylinder 40, instead of extending beyond the gun as illustrated, may be arranged alongside the gun. The present arrangement is preferable when the available tunnel space permits of its use. The gun 15 may be mounted on any desirable means.

Parts not specifically referred to, are ordinary structural parts and consequently are not described. The word "concrete" is to be understood to refer to concrete, or to cement, 20 mortar or other like materials, and the term "air" is to be understood to mean and include any other suitable fluid substance.

Other modifications of the device herein described in detail are possible within the 25 purview of my invention and therefore I desire not to be limited to an interpretation narrower than set forth in the claims.

I claim:

1. A pneumatic concrete gun comprising 30 a closed container tapering at its lower portion to an outlet opening and having an aperture therethrough opposite said opening, a blower pipe slidably mounted in said aperture, a nozzle at the end of said pipe, a piston 35 connected to said pipe, a cylinder surrounding said piston, means for selectively supplying compressed air to either side of said piston, means permitting passage of compressed air from one side of said piston into said pipe, 40 and means for preventing passage of concrete into said cylinder.

2. In a pneumatic concrete gun for forcibly ejecting concrete, a closed container having a discharge opening for the concrete, a 45 source of compressed air for impelling the concrete, a tapered nozzle adapted to discharge air along the lower wall of the container and having apertures in the upper and outer portions thereof for discharging air upward and sideways, and means for moving 50 said nozzle along the lower wall of the container.

3. In a pneumatic concrete gun for forcibly ejecting concrete, a closed container having a discharge opening for the concrete, a source of compressed air for impelling the concrete, a tapered nozzle adapted to discharge air along the lower wall of the container and having apertures in the upper and outer portions thereof for discharging air upward and sideways, means for restraining 60 said nozzle against angular displacement, and means for moving said nozzle along the lower wall of the container.

65 4. A pneumatic concrete gun comprising a

container having a discharge opening from its lower portion and an aperture therethrough opposite said opening, a blower pipe slidably engaged in said aperture, a nozzle at the end of said pipe, a piston connected to 70 said pipe, a cylinder surrounding said piston, means for selectively supplying compressed air to either side of said piston, and means permitting passage of compressed air from one side of said piston into said pipe.

75 In testimony whereof, I affix my signature.
